UNITED STATES PATENT OFFICE.

SILAS J. CRITES, OF ASHLAND, OHIO, ASSIGNOR OF ONE-HALF TO J. C. HISSEM, OF SAME PLACE.

ROPE-FASTENER.

SPECIFICATION forming part of Letters Patent No. 321,799, dated July 7, 1885.

Application filed August 25, 1884. (No model.)

To all whom it may concern:

Be it known that I, SILAS J. CRITES, of Ashland, in the county of Ashland and State of Ohio, have invented certain new and useful 5 Improvements in Rope-Fasteners; and I do hereby declare the following to be a full, clear, and exact description of the invention, such as will enable others skilled in the art to which it pertains to make and use the same.

10 My invention relates to means for securing a rope to a hoisting-hook or similar device, the object being to combine simplicity and economy of construction with security and durability in use.

15 The invention consists in the improved construction and combinations of parts hereinafter fully described, and pointed out in the claim.

20 The drawing is a vertical section of a rope-clamp constructed in accordance with my invention.

25 In the accompanying drawing, A represents my improved clamp, which consists of two independent sections, B B, semicircular in cross section. These sections B B are provided on their inner sides or walls with inwardly-extending integral spurs or spuds C. The said sections B B are also provided near their upper ends with registering openings

a, for the passage of a headed bolt, b, threaded at its end to receive a nut, as shown, whereby said sections may be firmly and securely held together. The lower ends of the sections B B are provided on their inner sides with beveled edges d, and said sections are also formed with grooves in which a clamping-ring, E, is adapted to be seated. When the ring E is placed upon the lower ends of the sections, their opposite ends are pressed together and bolted, as shown, thereby preventing the displacement or detachment of the clamping-ring.

30 Having fully described my invention, what I claim as new, and desire to secure by Letters Patent, is—

35 A rope-clamp consisting of two independent sections having spurs on their inner sides, a bolt securing said sections together at one end, the other ends of said sections being beveled on their inner sides, and a clamping-ring, sub- 40 substantially as set forth.

45 In testimony whereof I have signed this specification in the presence of two subscribing witnesses.

SILAS J. CRITES.
